CALISTO J. MONFREDINI, OF BOSTON, MASSACHUSETTS.

PNEUMATIC ACTION FOR MUSICAL INSTRUMENTS.

1,078,688.

Specification of Letters Patent.

Patented Nov. 18, 1913.

Application filed April 4, 1913. Serial No. 758,817.

To all whom it may concern:

Be it known that I, CALISTO J. MONFREDINI, a subject of the King of Italy, residing at Boston, in the county of Suffolk and State of Massachusetts, have invented new and useful Improvements in Pneumatic Actions for Musical Instruments, of which the following is a specification.

This invention relates to pneumatic actions for musical instruments and has for its object the producing of an inexpensive, compact and durable device for controlling the action of the tone producing instrumentalities, said device being detachably secured in place to permit its removal to inspect and repair the various parts thereof.

The invention consists in the combination and arrangement of parts whereby the above object and certain other objects hereinafter appearing may be attained, as set forth in the following specification and particularly pointed out in the claims.

Referring to the drawings: Figure 1 is a rear elevation of a portion of a pneumatic action embodying my invention, parts of said device being shown in section and other parts broken away to more clearly illustrate the same. Fig. 2 is a sectional elevation taken on line 2-2 of Fig. 1.

Like numerals refer to like parts throughout the several views of the drawings.

In the drawings, 4 is a suction chest which is of the usual form and arranged longitudinally of the instrument of which the device forms a part, and comprising a chamber 5 from which the air is exhausted in the usual manner. Connected to the suction chest 4, preferably to the bottom thereof, is a series of bellows 6 the movable member 7 of which is connected through a link 8 to the tone producing instrumentalities in the usual manner. A tracker board 9, preferably of the usual construction, is connected by means of a tube 10 to an air passage 11 preferably extending through the lower portion of the suction chest 4, said tracker board co-operating with the music sheet 12 in permitting air to enter said suction chest through the tube 10 and air passage 11, at the proper time.

The suction chest 4 is provided with passages 13 which lead from the suction chamber 5 outwardly to the outer wall 14 of said chest, said passages 13 being uniformly spaced throughout the length of said suction chest. The air passage 11 also extends

through said suction chest to said rear wall 14 thereof, preferably beneath the passage 13, while a third passage or channel 15 extends from said rear wall through a portion of the suction chest 4 and into the bellows 6, said passages 13, 11 and 15 of the respective sets being arranged substantially in the same vertical plane. A valve shell 16 is detachably secured in contact with the wall 14 of said suction chest to cover all of said passages included in one set, said shell being secured to said chest by means of screws 17 extending through plates 18 arranged transversely of said shells, the distances between the centers of one set of passages and the next adjacent sets of passages being preferably equal to the diameters of said shells, thus permitting said shells to be arranged in contact with said chest and in contact with the adjacent shells.

The valve shell 16 is also provided with a suction chamber 19 which is a continuation of the passage 13 connecting said suction chamber with the main suction chamber 5. Leading outwardly from the suction chamber 19, substantially in opposite directions, are ports 20 and 21, said ports being provided with disks 22 and 23 respectively which are adapted to close said ports during certain times in the operation of the device.

The valve disk 22 is preferably secured to a diaphragm 24 which is arranged within a chamber 25 formed in said shell 16 above a recess 26, while the valve 23 is secured to a valve stem 27 which is reciprocatorily arranged in guides 28 and 29, mounted in the ports 20 and 21 respectively, said valve stem normally contacting with the disk 22 and adapted to be moved by said disk upon the deflection of the diaphragm 24.

The recess 26 is connected by means of a passage 30 with the chamber 25, while a second passage 31 connects said recess 26 with the air passage 11, all of said passages uniting to provide communication between said tracker board and said suction chamber 5, said passages 30 and 31 being arranged within the shell 16, but particularly in a detachable diaphragm supporting member 32 which contains said recess 26 and the diaphragm 24 permitting the removal of said diaphragm from said shell to replace the same, said member being preferably held, at one side thereof, in place in said shell by a tapering side 33 which engages

a correspondingly tapering wall 34 of the chamber 25, a contact between said member 32 and the tapering wall 34 being maintained by the wall 14 of the suction chest 5 in contacting with said member. The shell 16 further comprises a main suction channel 35 which connects the port 21 with the channel 15. Said shell 16 is still further provided with a screw-threaded cap 36 10 which may be removed when desired to permit free access to the valve 23, said cap having an air inlet passage 37 extending longitudinally of said cap and in alinement with the median axial line of the valve stem 27, 15 while a series of laterally disposed ports 38 constitute the mouth of said inlet passage. The lower end of the cap 36 constitutes a seat for the valve 23 when said valve is moved by the deflection of the diaphragm 24, thus closing said inlet passage when said valve is seated thereagainst.

The general operation of the device hereinbefore specifically described is as follows: The air in the suction chamber 5 is exhausted in a manner well known to those skilled in the art and as long as said suction is maintained and air is admitted to said shell through no other source than the passage 27, there will be a tendency, by reason 25 thereof, for the valve 23 to remain in contact with the partition in the shell 16 comprising the port 21 thus closing said port. Furthermore the suction in said chamber acting through the port 20, chamber 25, passage 30 and recess 26 tends to retain the diaphragm 24 in its position indicated in full lines Figs. 1 and 2, providing no air is permitted to enter the passage 11. When however the music sheet 12 is moved to bring one 30 of the perforations *a* therein into alinement with the hole *b* in the tracker board 9 the air at atmospheric pressure will be suddenly forced, in its attempt to enter the suction chamber 5 through the tube 10 and air passage 11 into the recess 26 beneath and against said diaphragm 24, certain portions of said air escaping through the passage 30 which is substantially smaller in area than the air passage 31. In consequence of the 35 difference in areas between the diaphragm 24 and the valve disk 23 said diaphragm which is the larger will be deflected and by said deflection the valve 22 will be moved from its position illustrated in full lines 40 Fig. 2 to that illustrated in dotted lines in said figure or against the partition comprising the port 20 and thereby close said port and preventing the admission of air therethrough with the exception of a very small 45 amount which may leak therethrough owing to the impossibility of making a valve of this nature absolutely air tight. This leakage however is necessary in the operation of the device as it removes a certain amount of 50 air from the chamber 25, which has entered

said chamber through the passage 30. It would seem in view of this statement that the valve 22 would be unnecessary. This valve however is provided for the purpose of limiting the amount of air which may be drawn through the port 20 at a time when the opening in the music sheet alines with the passage *b*, for should the air be permitted to be uninterruptedly drawn through the port 20 the suction creating devices 55 would be unduly taxed or rendered inadequate to maintain a suction in the chamber 5 sufficient to collapse the bellows 6. Then again if the passage 30 were to be made smaller in order to limit the amount of air 60 passing therethrough the return movement of the diaphragm would be retarded.

Simultaneously with the closing of the port 20 the port 21 will be opened by reason of the fact that the stem 27, which carries the valve 23, contacts with the face of the valve 22, and as said valve moves upwardly the valve 23 will likewise be moved from its position illustrated in full lines Fig. 2 to that illustrated in dotted lines in said figure 65 and into contact with the under face of the cap 36. By the closing of the passage 37 by the valve 23 in its upward movement the supply of air through said passage into the main suction channel 35 will be cut off and the air remaining in said passage will be exhausted through the port 21, by means of the suction in the suction chamber 5, and by this action the bellows 6 will be collapsed, that is to say, the movable member 7 will be 70 drawn toward the stationary member 39 and actuate the tone producing instrumentalities through the link 8 in the usual manner, not shown in the drawings, the pressure at this time against the diaphragm 24 being greater than that against the valve 23, thereby overcomes the tendency of the valve 23 to descend. In this condition the valves are maintained as long as the perforations in the music sheet 12 aline with the hole *b* permitting the air to enter therethrough, but as said music sheet moves along over said opening and gradually closes the same, the supply of air will be cut off through the 75 passage 11 and the pressure of the air through the holes 38 and passage 37 will overcome the pressure against the diaphragm 24 owing, as hereinbefore stated, to the exhaustion of the air in the chamber 26 through the passage 30 and port 20 even 80 though the valve 22 be closed and cause a reaction thereof which results in the closing of the ports 21 by the valve 23 and permitting the air to rush through the ports 38 and suction channel 35 into the bellows 6, 85 causing the same to open as indicated in Fig. 2, which is the normal condition thereof.

When it is desired to replace the disk 23, the cap 36 is unscrewed and the stem 29 90

withdrawn without disturbing any of the associated parts of the device.

To remove the disk 22 or the diaphragm 24 from any one of the shells 16, the screw 17 which secures that shell in contact with the suction chest are removed and said shell may then be withdrawn from contact with the face 14. This operation exposes the member 35 which may be removed from the chamber 25 and said disk 22 will be exposed to view and may be easily removed and replaced if so desired.

Having thus described my invention, what I claim and desire by Letters Patent to secure is:

1. A pneumatic action for musical instruments having, in combination, a suction chest, a tracker-board, a valve shell detachably secured to said chest comprising a chamber communicating with said suction chest, and two ports leading from said suction chamber substantially in opposite directions, valves for said ports respectively, and a diaphragm adapted to be moved by the passage of air through said tracker boards to operate said valves to close one and open the other of said ports.

2. A pneumatic action for musical instruments having, in combination, a suction chest, a bellows, a tracker board, a valve shell detachably secured to said chest comprising two ports opening into said chest, one of said ports being connected by a channel extending through said shell to said bel-

lows, the other of said ports being connected by passages extending through said shell to said tracker board, a valve for each of said ports respectively, and a diaphragm arranged within said shell adapted to be moved in one direction by the admission of air through the port connected with said tracker board to close that port and open the port connected with said bellows, said diaphragm adapted to be moved in the opposite direction by the cutting off of the supply of air from said tracker board, to move said valve in the opposite direction.

3. A pneumatic action for musical instruments embodying, in its construction, a valve shell having a chamber open at one side thereof, the wall of said chamber opposite said opening inclining inwardly from the bottom of said chamber upwardly, and a diaphragm supporting member detachably arranged within said chamber, the inner side of said support engaging said inclined wall and the outer side of said support alining with the open side of said shell, whereby said member may be retained in its proper position.

In testimony whereof I have hereunto set my hand in presence of two subscribing witnesses..

CALISTO J. MONFREDINI.
